UNITED STATES PATENT OFFICE.

WINSLOW R. PARSONS, OF WATERLOO, IOWA.

BRAIDING ATTACHMENT FOR SEWING-MACHINES.

SPECIFICATION forming part of Letters Patent No. 290,465, dated December 18, 1883.

Application filed October 20, 1882. (No model.)

To all whom it may concern:

Be it known that I, WINSLOW R. PARSONS, of Waterloo, in the county of Black Hawk and State of Iowa, a citizen of the United States of America, have invented certain new and useful Improvements in Under-Braider Attachments for Sewing-Machines, of which the following, in connection with the accompanying drawings, is a specification.

10 In the drawings, Figure 1 is a top or plan view of that part of a sewing-machine embodying my improvements. Fig. 2 is bottom view of the throat-plate and shuttle-race slides. Fig. 3 is a section on a larger scale in the plane of the line $x\ x$ of Fig. 2. Fig. 4 is a face view of the sewing-machine head, the face-plate being shown as partly broken away to show the interior parts. Fig. 5 is a section in the plane of the line $x'\ x'$ of Fig. 4; and Fig. 6 is a detail view, in perspective, of one of the braid-pressers. Fig. 7 is a large-scale perspective view of the throat-plate with its spring, as shown in section in Fig. 3.

Like letters of reference indicate like parts.

25 A represents the throat-plate, and a a braid-passage in the form of an open groove, hereinafter termed the "groove a ," in the upper side or face thereof.

B is a spring applied to the plate A and arranged in the groove a . The free end of the spring B yields downwardly, and is adapted to permit of the passage of the needle C, b being the needle-hole.

D is one of the shuttle-race slides. This slide has in its under side or face a longitudinal groove, a' , meeting the groove a , which extends in the same direction as the groove a' to a point beyond the needle-hole, and, by preference, as shown in the drawings, to or 40 into the feed-hole or opening for the feed marked f . (See Figs. 1, 3, and 7.) The object of thus extending the groove a is to provide for supporting the braid beyond the needle, so as to keep it from turning too abruptly, and thus passing to one side of the needle, which causes the needle to miss the braid altogether frequently, in using other under-braiders, when braiding around corners or in small circles or curves. The extended groove a holds the braid from moving sidewise until it

has fully passed the needle, and thus obviates this trouble, while the cloth is free to turn independently. The operator is thus enabled to turn corners and braid in curves with great facility and nicety. It is, of course, essential 55 that the braid-passage at and beyond the needle-hole shall be in form or effect an open groove, as shown at a ; but as regards that important feature of my invention just set forth, that part of the braid-passage leading to the 60 needle may be of other known forms without change in the mode of operation or the effects produced.

E is a tongue, extending from the plate D and extending freely over the spring B. The 65 free or yielding end of the spring B is intended to meet, or nearly meet, the tongue E, as is clearly shown in Fig. 3.

In practice the braid is laid in or fed through the groove a' toward the needle, and passes 70 between the parts B and E, the former of which yields readily to any inequalities of thickness in the braid, and yet retains it properly in its place or position during work. Such is the function performed by the tongue and spring, 75 and the difficulty heretofore experienced on account of unevenness in the thickness of the braid is thereby avoided, for it is obvious that a braid having some parts even slightly thicker than others would be liable to be retarded in 80 its passage through the braider, and thus cause the goods to be bunched up or gathered, whereas a yielding or spring pressure on the braid would permit a uniform movement of the braid, or a free movement thereof, with 85 the goods as the latter are fed to the needle by means of the feed mechanism. It will also be perceived that the parts B and E also adapt the braider to braids differing from each other in thickness as well as to unequal thickness in 90 the same braid.

In order to prevent the braid from being turned laterally from its proper course, I deem it preferable, though not absolutely essential, to slightly arch or bevel the under side of the 95 tongue E at its free end, as indicated at c , Fig. 6.

In applying braids to goods by means of sewing-machines it is frequently necessary to turn the goods or move them so that the braid 100

may be attached in various designs. The presser-foot, by resting constantly on the goods, prevents the goods from being moved with facility for the purpose referred to.

5 To obviate the objection I employ the following means:

F is a presser-foot, and F' is the presser-foot bar.

G is an arm or lifter, the lower end of which 10 is fitted movably upon the square portion of the bar F', and the upper end of which is curved or bent to project horizontally away from the said bar, as shown.

H is a set-screw passing through the lower 15 part of the lifter G, and having its inner end or point in contact with the bar F', thereby securing the part G adjustably to the bar F', or so that it may be moved up and down thereon and secured in any position in which it 20 may be set.

I is a slot in the face-plate. This slot is located in the back of the face-plate, and the screw H passes through the slot I, as shown. By this means the exposed end of the screw H 25 is conveniently accessible, and may be made tight or loose and raised or lowered for the purpose of adjusting the lifter G vertically on the presser-foot bar.

J is the end disk of the horizontal shaft of 30 the machine, and d is a small pin or stud projecting therefrom. This pin is arranged directly opposite the roller K, which vibrates the needle as the said shaft is rotated, and the upper or horizontal part of the lifter G is arranged, as shown, to be struck and raised by 35 the pin d each time said shaft is once rotated. By this means the presser-foot will be raised from the goods while the needle is in the goods, and the latter may then be turned on the needle as a pivot, thereby admitting of the goods being turned with facility, so that the braid 40 may be evenly stitched thereto in various patterns or designs.

It will be perceived that the lifter G may

be raised or adjusted either so as not to be struck by the pin d when no braiding is to be done, or that it may be so adjusted that its movement will be greater or less, as may be desired.

Having thus described my invention, what I claim as new, and desire to secure by Letters Patent, is—

1. In an under-braider, a throat-plate constructed with a braid-passage and a needle-hole, said braid-passage extending beyond 55 said needle-hole, substantially as herein described, for the purpose set forth.

2. The combination, in an under-braider, of a throat-plate, A, having a groove, a, in its upper side to form the terminal end of the braid-passage, with a needle-hole, b, within said groove, said groove extending beyond the needle-hole, and a cover or tongue, E, overlying the braid within said groove, substantially as herein specified. 60

3. The combination of the throat-plate A, having in its upper side the braid-groove a, and the braid-pressing spring B, having therein a needle-hole, and arranged substantially as shown and described with relation to the 70 needle, for the purposes specified.

4. The combination, with the braid-grooves of an under-braider, of a spring adapted and arranged to press the braid yieldingly on its passage to the needle, and the tongue E, having in its free or outer end a bevel or arch, c, 75 substantially as and for the purposes specified.

5. The combination, in an under-braider, of the grooved throat-plate A, the spring B, the grooved shuttle-race slide D, and the tongue 80 E, all arranged substantially as shown and described with relation to each other, for the purposes set forth.

WINSLOW R. PARSONS.
